[57] CLAIM

The original design for a numerically controlled lathe, as shown and described.

DESCRIPTION

FIG. 1 is a perspective view of the numerically controlled lathe;

FIG. 2 is a top plan view of the numerically controlled lathe;
FIG. 3 is a front plan view of the numerically controlled lathe;

FIG. 4 is a left plan view of the numerically controlled lathe;
FIG. 5 is a right plan view of the numerically controlled lathe;

FIG. 6 is a bottom plan view of the numerically controlled lathe;

FIG. 7 is a rear plan view of the numerically controlled lathe;

FIG. 8 is a perspective view of the another embodiment of the numerically controlled lathe of the present invention;

FIG. 9 is a top plan view of another embodiment of FIG. 8;

FIG. 10 is a front plan view of another embodiment of FIG. 8;

FIG. 11 is a left plan view of another embodiment of FIG. 8;

FIG. 12 is a right plan view of another embodiment of FIG. 8;

FIG. 13 is a bottom plan view of another embodiment of FIG. 8; and,

FIG. 14 is a rear plan view of another embodiment of FIG. 8.
